ABSTRACT

An ink jet cartridge has a recording head with a substrate, a head portion with a discharge port surface on the substrate, a discharge port provided on the discharge port surface, and an ink tank, the substrate having a leading end line. The ink tank has a substantially rectangular parallelopipedal shape and can contain ink. The ink tank includes a front surface, side surface, and opposing surface opposed to the side surface, the recording head is disposed on the side surface of the ink tank, and the opposing surface has a front end line. Plural positioning portions are provided on and project from the substrate of the head and part of the ink tank. The positioning portions project only within a space enclosed by a plane, the front surface of the ink tank, and the substrate. The leading end line of the substrate of the recording head and the front end line of the surface opposed to the side surface of the ink tank on which the recording head is disposed lie in the plane.

INK JET CARTRIDGE HAVING PROTECTED POSITIONING PORTIONS

This application is a continuation of application Ser. No. 08/076,115 filed Jun. 14, 1993, now abandoned, which is a division of application Ser. No. 07/458,539 filed Dec. 28, 1989, now U.S. Pat. No. 5,245,361.

BACKGROUND OF THE INVENTION

1. Field of the Invention

This invention relates to an ink jet recording apparatus to be employed for copying device, facsimile, word processor, video output printer, output printer of computer, etc., particularly to a constitution for mounting an ink jet cartridge having a recording head and an ink tank for containing ink freely detachably onto the carriage as the recording cartridge mounting means.

2. Related Background Art

Of the ink jet recording apparatus, there has been known one using an ink jet recording cartridge such as disposable cartridge comprising internally an integrated combination of an ink tank for housing ink which is a recording medium and a recording head element having the function of discharging ink (hereinafter called an ink jet cartridge). The term "cartridge" therefore refers to an assembly having a recording head portion and an ink tank. The cartridge is removably mounted on the carriage of an ink jet apparatus. The term "recording head" refers to a recording head portion having recording elements.

Examples of the mounting methods of such heads, including ink jet cartridges having recording heads, are described in U.S. Pat. No. 4,599,625 (Terasawa et al), U.S. Pat. 4,630,078 (Watanabe), U.S. Pat. No. 4,633,274 (Matsuda), U.S. Pat. 4,635,080 (Watanabe), U.S. Pat. No. 4,712,172 (Kiyohara et al), U.S. Pat. 4,727,384 (Tsuda), etc.

In mounting such recording head onto the carriage on the main body side of the recording device, since recording must be performed by attaching ink accurately to the adequate position on the recording paper, and the connecting terminal for transmitting recording signals adequately, it has been required to fix and mount the recording head at an adequate position.

To classify broadly the mounting methods of recording heads, there may be included the methods in which the ink cartridge having a recording head is mounted from above or behind of the carriage in parallel or by simple rotation.

As an example which performs mounting simply, there is such constitution as shown in FIG. 1. 101 is an ink jet cartridge of the type integrated with an ink tank, having a connecting terminals 101a having a plurality of electrical pads 111 and a discharge port surface of the ink recording head element 101c provided at the bottom. The carriage 102 is provided with a connecting terminal 102a for transmitting recording signals to the recording head. Here, 102a is constituted of a plurality of electrical pads 112 and 104 is a guide shaft for guiding movement of the carriage 102. Thus, when the cartridge is mounted from above the carriage, attachment and detachment can be done very easily, but since the connecting terminals 101a and 102a are not rubbed with each other during mounting and therefore, if there was a coating or a foreign matter due to ink contamination interposed between the connecting terminals, defective connection sometimes occurred. Also, an unused cartridge may sometimes have a very thin insulating protective film 121 provided for protection of connecting terminals. Then, in the

case of such mounting method, there is no action of ensuring connection by scraping off the protective film. Therefore, this example could never be said as the optimum example as the connecting method of signal terminals. Also, in commencing use after mounting an unused cartridge, it is necessary to form immediately the state where ink can be well discharge by means of a discharged restoration means, etc.

Accordingly, the present invention entails attaching and detaching the cartridge at the home position which becomes the waiting position of the cartridge, and protecting the discharge port preferably on completion of mounting of the cartridge.

FIG. 2A, as an example based on the above thought, 15 mounts a cartridge from behind the carriage. Similarly as in FIG. 1, 101 is the cartridge and 102 is the carriage. Here, 103 is a discharge restoration device equipped with a cap for protecting the discharge port of the recording head and preventing ink fixing. The constitution is such that, by 20 performing mounting of the recording head by inserting the cartridge 101 from behind the carriage 102 in the direction of the arrowhead, the recording head of cartridge 101 is capped at the fixed position, and the connecting terminals 101a and 102a are correctly connected. However, according to such method, the connecting terminals will be respectively rubbed during mounting successively. Particularly, the electrode pad 101 of the connecting terminal of the recording head located on the discharging port side will be rubbed with all the electrode pads of the carriage 102. Therefore, a 25 part of all of the terminals will be considerably damaged, whereby it has been found that electrical signals cannot be transmitted to cause defective discharging.

Accordingly, the present inventors have further thought of 30 a method of mounting by rotation of the cartridge 101 as shown in FIG. 2B, but with such constitution, mounting must be done with the discharge port surface 101b which 35 becomes the front surface of the cartridge 101, particularly the upper part of 101b, being positioned greatly forward before the constant position after mounting. Then, a great 40 space is required in front of the carriage. However, when good ink discharging is considered, since the interval between the recording head and the recording paper is designed to be 3.0 mm or less, and therefore it has been 45 found to be difficult to take such constitution. Also, even if mounting may be effected at the home position, because great mutual interference with the cap cannot be avoided, such inconvenience as deformation of cap, etc. has been 50 found to occur.

SUMMARY OF THE INVENTION

The present invention has been accomplished in view of these technical tasks of the prior art and the findings by the present inventors. Shortly speaking, an object of the present invention is to provide a cartridge capable of effecting electrical connection in connecting the connecting terminals without damaging terminals and which can also scrape off the protective film provided on the terminal surface by mutual rubbing of the terminals with each other, and capable of positioning surely the recording head simultaneously with mounting completion of the cartridge and a member for mounting of cartridge and a cartridge mounting method and an ink jet recording device.

Another object of the present invention is to provide a 60 tank integrated type cartridge which can accurately position an ink tank integrated with a recording head as the cartridge onto the carriage of an ink jet recording device, to provide 65

a carriage which can more surely hold said cartridge and to provide an ink jet recording device having a recording head which can be accurately held under the desired state relative to within the main body of the device and a carriage. Another object of the present invention is to provide a constitution which can elongate the life of the positioning portion of said head itself which as part of the cartridge is detachable and the cap within the main body.

BRIEF DESCRIPTION OF THE DRAWINGS

FIG. 1, comprising FIGS. 1A and 1B, is a schematic side view showing a prior art example of the mounting actuation of a c ridge.

FIG. 2A is a schematic side view showing an example of the mounting actuation of a recording head of a cartridge.

FIG. 2B is a schematic side view showing an example of the mounting actuation of a recording head of a cartridge.

FIG. 3 is a schematic perspective view showing the ink jet recording device according to the first embodiment of the present invention.

FIG. 4 is a schematic perspective view showing the constitution of the cartridge according to the first embodiment of the present invention.

FIGS. 5A and 5B are a schematic perspective view and a top view showing the constitution of the carriage according to the first embodiment of the present invention.

FIGS. 6A to 6D are schematic illustrations showing the mounting actuation of the cartridge according to the first embodiment of the present invention.

FIGS. 7A to 7E are schematic illustrations showing the manner of connection of the cartridge and the connecting terminals of the carriage according to the first embodiment of the present invention.

FIGS. 8A and 8B are schematic partially enlarged views showing the manner of connection of the connecting pads in FIGS. 5A to 5E.

FIG. 9 is a schematic perspective view showing the ink jet recording device according to the second embodiment of the present invention.

FIGS. 10A and 10B are a schematic perspective view and a sectional view showing the constitution of the cartridge according to the second embodiment of the present invention.

FIGS. 11A and 11B are a schematic perspective view and a top view showing the constitution of the second embodiment of the present invention.

FIGS. 12 to 12D are schematic illustrations showing the mounting actuation of the cartridge according to the second embodiment of the present invention.

FIG. 13A to 13E are schematic illustrations showing the manner of the connecting terminal according to the present invention.

FIGS. 14A and 14B are schematic partially enlarged views showing the manner of connection of the connecting pads in FIGS. 13A to 13E.

FIG. 15 is a perspective view of the ink jet recording device according to the third embodiment of the present invention.

FIGS. 16A to 16C are, respectively, a perspective view of the cartridge to be mounted on the printer shown in FIG. 15 as viewed from the bottom side, its perspective view as viewed from the top side, and its bottom view.

FIG. 17 is a schematic sectional view for illustration of the internal constitution of the cartridge shown in FIGS. 16A to 16C.

FIGS. 18A to 18C are, respectively, a perspective view, a top view and a back view showing schematically the constitution of the carriage for mounting its cartridge.

FIG. 19 to 22c are schematic illustrations for explanation of the actuation during mounting of the cartridge according to the third embodiment onto the carriage.

DETAILED DESCRIPTION OF THE PREFERRED EMBODIMENTS

The present invention is described below by referring to a plurality of embodiments, but the present invention is not limited by these but includes many modified embodiments, provided that the object of the present invention can be accomplished.

As used in this specification, the term "ink jet cartridge" refers to a combination of an ink jet recording head and an ink tank. The term "recording head which can be replaceable" refers to the recording head which is used in such an ink jet cartridge, and the term "ink tank which can be replaceable" refers to the ink tank which is used in such an ink jet cartridge. For simplicity, the terms "cartridge", "recording head" and "ink tank" may be used alone. The term "cartridge" is always meant to refer to the combination of the recording head and ink tank, rather than either of those components alone."

The present invention is a constitution which can perform positioning of the cartridge having the recording head and the carriage with good precision, and with such constitution, accurate positioning of the ink discharge port, and accurate positioning capable of joining pads as unit elements of electrical connecting terminals while rubbing with each other, one to one, can be done.

In the following, the respective embodiments are to be described in detail.

FIRST EMBODIMENT

This embodiment is a cartridge having an ink jet recording head having a discharge port for discharging ink and an energy generation means for generating energy for discharging ink, which cartridge is detachable relative to the mounting means for mounting the cartridge with the recording head of ink jet recording means, characterized in that the cartridge has a surface having the discharge port provided thereon, an electrical connecting terminal provided on a surface forming a specific angle with respect to the surface and a rotation center portion in attachment and detachment relative to the mounting means of the cartridge, the center axis of the rotation center portion is substantially parallel to the surface where the discharge port is provided and the surface where the connecting terminal is provided, with its position being made on the side opposed to the connecting terminal with respect to the surface where the discharge port is provided and outside the range where the discharge port is provided, and on the discharge port side relative to the connecting terminal near the surface side where the discharge port is provided.

Also, this embodiment is an ink jet recording device, comprising an ink jet cartridge having a discharge port for discharging ink and energy generation means for generating energy for discharging ink, wherein the cartridge has a surface having the discharge port provided thereon, an electrical connecting terminal provided on a surface forming a specific angle with respect to the surface and a rotation center portion in attachment and detachment relative to the mounting means of the cartridge, the center axis of the

rotation center portion is substantially parallel to the surface where the discharge port is provided and the surface where the connecting terminal is provided, with its position being made on the side opposed to the connecting terminal with respect to the surface where the discharge port is provided and outside the range where the discharge port is provided, and on the discharge port side relative to the connecting terminal near the surface side where the discharge port is provided and a mounting means having a site to be engaged to the rotation center for mounting the cartridge.

Further, this embodiment is a method for mounting a cartridge having recording head having a discharge port for discharging ink, an energy generation means for generating the energy for discharge of the ink through the discharge port and an electrical connecting terminal provided on a surface forming a specific angle with respect to the surface where the discharge port is provided, characterized in that the cartridge is mounted by engaging the rotation center portion having a center axis in parallel to both the surface where the discharge port is provided and the surface where the connecting terminal is provided and located on the side opposed to the connecting terminal with respect to the surface where the discharge port is provided, outside of the range where the discharge port is provided and on the discharge port side relative to the connecting terminal near the surface side where the discharge port is provided, to the site corresponding to the mounting means with the rotation center portion as the center.

Referring now to FIGS. 3 through FIG. 8B, this embodiment is described specifically and in detail.

FIG. 3 is a schematic perspective view of the principal part of the recording device. FIG. 4 is a schematic perspective view of the cartridge according to the embodiment of the present invention as viewed from the bottom side, and FIG. 5A is a schematic perspective view according to this embodiment, and FIG. 5B is a schematic plan view of the carriage of this embodiment as viewed from above.

First, in FIG. 3 the carriage 20 as the mounting means having the cartridge 10 mounted thereon moves along the paper delivery roller 60 as guided by the guide shaft 40. The constitution is made such that the cartridge 10 discharges ink toward the surface of the recording paper P as the recording medium, and forms an image with the attached ink droplets, thereby performing recording. Numeral 30 is the discharge restoration means located at the home position of the carriage 20. The discharge restoration means is constituted of a cap 31 comprising an elastic material such as rubber, etc. provided for protecting the discharge port by covering over the discharge port and also preventing fixing of ink by prevention of drying of the discharge port vicinity including the discharge port, and a suction pump 33 communicated to the cap 31 through an elastic tube 32. By sucking ink and/or air through the discharge port by reducing the pressure internally of the cap 31 with the pump 33, the discharging state of ink can be made good. The carriage 20 is located at the home position as the non-recording position except when the cartridge 10 performs recording, so that the discharge port may be protected there with the cap 31. And, the constitution is made so that attachment and detachment of the cartridge 10 must be performed necessarily at the home position.

This can be done by controlling electrically the motor (not shown) for driving the carriage.

Next, by referring to FIG. 4, the constitution of the cartridge 10 is described. In these Figures, the cartridge 10 of the ink tank integration type is equipped with a recording

head element 10C provided with an electrothermal transducer not shown as the energy generation means for generating thermal energy as the energy to be utilized for discharging of ink (in combination, the recording head and ink tank are called a cartridge). For such recording head element, a piezoelectric element, etc. can be alternatively employed as the energy generation means. However, the constitution by use of the electrothermal transducer as mentioned above having the advantages of simple 10 constitution, lowered production cost and possibility of high densification may be preferably utilized.

Numerals 10a is a connecting terminal for transmitting the recording signal (electrical signal), 10b a guide pin which becomes the rotation center of the cartridge 1 during attachment and detachment relative to the carriage 20 by fitting to the carriage 20 as described below. The recording head element 10c is provided with a plurality of ink discharge ports 10d on the front surface. The connecting terminal 10a is provided with a concavity 10f which is a portion recessed by about 1 to 2 mm toward inside with longitudinal length X=35 mm and lateral length Y=10 mm for preventing contamination with ink, etc. and deformation, etc. of the connecting terminal 10a by touching with hands during handling. Behind the cartridge is provided a fixing hook 10g (see FIG. 6A) for fixing the cartridge through engagement with the nail portion of the carriage 20.

Referring now to FIGS. 5A and 5B, the constitution of the carriage 20 is described. In these, Figures, 20a is the connecting terminal to be connected to the connecting terminal 10a of the cartridge 10, 20b the fitting portion fitted (engaged) to the guide pin 10b of the recording head 10, 20c the elastic member for giving an adequate pressure contact force (20 to 50 g per one terminal) during connection of the connecting terminals 10a and 20a, for which chloroprene rubber, urethane rubber, molprene rubber, etc. may be used as preferable material for having optimum modulus of elasticity. Numeral 22 is a plate spring provided to taking balance with the pressure forces of connecting terminals 10a and 20a, and has the pop-up function during dismantling of the head as described below. Nail portion 23 is to be engaged with the fixing hook 10g of the cartridge 10 to fix and hold the cartridge 10 and 50 is a flexible cable for transmitting electrical signals from the recording control section not shown to the connecting terminal 20a of the carriage.

Here, although the description of the connecting terminal 20a is different between FIGS. 5A and 5B, this is done for simplification of the drawings, and the specific constitutions should be understood from the following description.

The mounting method of the cartridge in the constitution as described above is described in detail by referring to FIGS. 6A to 6D.

FIG. 6A shows the state of mounting initiation state, FIG. 6B the first state in the course of mounting, FIG. 6C the second state in the course of mounting and the FIG. 6D the state on completion of mounting.

First, as shown in FIG. 6A, when the cartridge 10 is placed on the carriage 20, the guide pin 10b of the cartridge 10 and the surface at the bottom of the head 10 are guided by the guide surface 20h and the tip end 20i of the lock lever 20l, and moves in the direction A in the Figure by the weight of the cartridge 1. Next, as shown in FIG. 6B, when the guide pin 10b is fitted into the fitting portion 20b, the rear end portion of the cartridge 10 comes off from the lock lever 20l, to rotate the guide pin 10b in the direction C with the guide pin 10b as the center, whereby the fixing hook 10g comes against the lock lever as shown in FIG. 6C. Next,

when the rear end of the cartridge 10 is compulsorily pushed down in direction D, the discharge port surface from the state as shown in FIG. 6C contacts little by little from its upper portion the elastic portion of the cap 31. Then, the connecting terminals 10a and 20a contact successively from the discharge outlet side, until finally the fixing hook 10g is hooked by the nail portion 23 of the lock lever 20i to become the state held by fixing as shown in FIG. 6D, whereby the connecting terminals 10a and 20a are correctly connected electrically and mechanically.

In the constitution capable of performing the actuation as described above, since the guide pin 10b, namely the rotation center of the cartridge 10 is provided within the range AR upwardly of the position corresponding to the cap and in front of the connecting terminal, the front surface (namely discharge port) and the cap 31 of the recording head element 10c, and the connecting terminals 10a and 20a are adequately contacted or connected with each other without interference with other portions.

Further, by slight rubbing mutually between the connecting terminals during mounting of the cartridge 10, foreign matters existing on the terminal surface can be also shaven off or scraped off to give the action of effecting sure electrical connection.

This manner is described in more detail by referring to FIGS. 7A to 7E and FIGS. 8A and 8B. FIGS. 7A through 7E show the manner in which the connecting terminals are bonded or connected to each other. FIGS. 8A and 8B are schematic illustrations partially enlarged of one of a plurality of electrode pads of connecting terminal, showing the states at the beginning of contact and on completion of connection.

The plural number of electrode pads 13 of the connecting terminal 10a of the cartridge 10 of this embodiment are made of lead frame of metal, etc., with the contact points being made flat. The plural number of electrode pads 24 of the connecting terminal 20a of the carriage 20 are worked into semispherical projected shapes by application of plating to the terminal on the flexible cable 50. Corresponding to the mounting actuation of the cartridge, the electrode pads from the discharge port side will contact from the state in FIG. 7A as shown in FIG. 7B, and successively as shown in FIG. 7C. In transferring from FIGS. 7B to 7E, the pads are rubbed mutually one to one to maintain good electrical contact.

The pressure contact force at the contact point of the pad is controlled through deformation of the elastic member 20c, whereby superfluous contact force can be absorbed to give adequate pressure contact force. When mounting of the cartridge is completed, as shown in FIG. 7E, the position of the connecting terminal 20a of the carriage is positioned lower than the position in FIG. 5A, whereby the pressure contact force is applied upwardly with the elastic member 20c. Such pressure contact force is balanced with the forces of the nail 23 and the fitting portion 20b of the carriage. Further, connection of the terminal is described in detail by referring to FIGS. 8A and 8B. In FIGS. 8A and 8B, I shows the contact position of the electrode pad 12 at the beginning of contact, and J the contact position of the electrode pads 13, 24 under the final state. Through the slippage k between the contact points, even when foreign matters may be adhered on the contact point terminal surface, they can be scraped off to effect sure electrical connection. For connection as described above ($k>0$) to be effected, the constitution is required to be made such that the rotation center as the standard for rotation should be positioned with a predetermined distance in the direction of the normal line 13-2 of the

contact portion of the electrode pad 13 of the cartridge from the tangential line 13-1 of the contact portion, and also the electrical pad 24 of the carriage 20 should be dislocated ($m>0$) when the cartridge 10 is mounted.

5 Next, the method for dismantling the cartridge 10 is to be described.

First, when the lock lever 20i is moved by pressing in the direction EJ in FIG. 6D as described above, the fixing hook 10g is disengaged from the nail 23 to release fixing of the cartridge. Then, by the plate spring 22 provided for taking balance with the connecting terminals 10a and 20a, the rear portion of the cartridge is hopped up through elastic force, and can be readily taken out.

Further, in the above-described embodiment of the present invention, the ink discharge port 10d, the electrical connecting terminal 10a are all provided on substantially one straight line in the recording head element 10c so as to hold readily the positional relationships of the respective elements with high precision. Also, in the present embodiment, further the above elements are provided on one end side where the cartridge is located, and further the cap is located on the above straight line in the home position. According to this constitution, the positioning member for carriage and electrical connecting terminals can be arranged 15 on one side of the cartridge and the carriage, whereby an extremely advantageous constitution in aspect of practical armoring such as withdrawing of flexible cable, etc. is given, and also unsure capping due to positional slippage can be prevented to make the probability of breaking of the cartridge and the cap accompanied with mounting actuation of the recording head much lower.

As described above, according to the mounting method of the first embodiment of the present invention, there is no breaking by way of rubbing of connecting terminals than is necessary and the cartridge will receive no bad influence from outside, and also, even if foreign matters may be attached on the terminal surface of the cartridge, they can be removed to effect mounting of the cartridge onto the correct position of the carriage with a force enough to obtain 20 electrical connection.

Also, attachment and detachment of the cartridge can be surely done while performing positioning with high precision.

SECOND EMBODIMENT

Next, the second embodiment according to the present invention is to be described.

Many points of the constitution of this embodiment are 35 the same as in the first embodiment as described above. The different point is that a positioning means for performing positioning with still better precision is provided.

More specifically, this embodiment is an ink jet recording head having a discharge port for discharging ink and an energy generation means for generating energy for discharging ink, which is detachable relative to the mounting means for mounting the cartridge onto an ink jet recording means, characterized in that the recording head has a surface having the discharge port provided thereon, an electrical connecting 40 terminal provided on a surface forming a specific angle with respect to the surface and a rotation center portion in attachment and detachment relative to the mounting means of the recording head, the center axis of the rotation center portion is substantially parallel to the surface where the discharge port is provided and the surface where the connecting terminal is provided, with its position being made on the side opposed to the connecting terminal with respect to 45 60 65

the surface where the discharge port is provided and outside the range where the discharge port is provided, and on the discharge port side relative to the connecting terminal near the surface side where the discharge port is provided, and further has a positioning member provided between the discharge port and the connecting terminal.

Further, it is an ink jet recording device, comprising having an ink jet recording head having a discharge port for discharging ink and an energy generation means for generating energy for discharging ink, wherein the cartridge has a surface having the discharge port provided thereon, an electrical connecting terminal provided on a surface forming a specific angle with respect to the surface and a rotation center portion in attachment and detachment relative to the mounting means of the cartridge, the center axis of the rotation center portion is substantially parallel to the surface where the discharge port is provided and the surface where the connecting terminal is provided, with its position being made on the side opposed to the connecting terminal with respect to the surface where the discharge port is provided and outside the range where the discharge port is provided, and on the discharge port side relative to the connecting terminal near the surface side where the discharge port is provided, further having a positioning means provided between the discharge port and the connecting terminal, and a mounting means having a member engaged with the positioning member for mounting the cartridge.

Referring now to the drawings of FIGS. 9 through 14B, one embodiment of the present invention is to be described specifically and in detail.

FIG. 9 is a schematic perspective view of appearance showing the principal part of the recording device. FIG. 10A is a schematic perspective view of the cartridge according to this embodiment of the present invention as viewed from the bottom side, FIG. 10B is a schematic plan view of the cartridge according to this embodiment, FIG. 11A is a schematic perspective view of the carriage according to this embodiment, and FIG. 11B is a schematic plan view of this embodiment as viewed from above.

First, in FIG. 9, the carriage 20 as the mounting means having the cartridge 10 mounted thereon moves along the paper delivery roller 60 as guided by the guide shaft 40. Cartridge 10 discharges ink toward the surface of the recording paper P as the recording medium, thereby forming an image with the attached ink droplets to effect recording. Numeral 30 is the discharge restoration means located at the home position of the carriage 20. The discharge restoration means is constituted of a cap 31 comprising an elastic material such as rubber, etc. provided for protecting the discharge port by covering over the discharge port and also preventing ink from depositing by prevention of drying of the discharge port vicinity including the discharge port, and a suction pump 33 communicated to the cap 31 through an elastic tube 32. By sucking ink and/or air through the discharge port by reducing the internal pressure of the cap 31 with the pump 33, the discharging state of ink can be made good. The carriage 20 is located at the home position as the non-recording position except when the cartridge 10 performs recording, so that the discharge port may be protected there with the cap 31. And, the constitution is made so that attachment and detachment of the cartridge 10 must be performed necessarily at the home position. The above-mentioned constitution is the same as in the first embodiment.

Next, by referring to FIGS. 10A and 10B, the constitution of the cartridge 10 is described. In these Figures, the

cartridge 10 of the ink tank integration type is equipped with a recording head element 10c provided with an electrothermal transducer not shown as the energy generation means for generating thermal energy as the energy to be utilized for discharging of ink. As the energy generation means to be employed for such recording head element, a piezoelectric element, etc. can be alternatively employed. However, the constitution by use of the electrothermal transducer as mentioned above having the advantages of simple constitution, lowered production cost and possibility of high densification may be preferably utilized.

Numerals 10a is a connecting terminal for transmitting the recording signal (electrical signal), 10b a guide pin which becomes the rotation center of the cartridge 1 during attachment and detachment relative to the carriage by fitting to the carriage 20 as described below. The recording head element 10c is provided with a plurality of ink discharge ports 10d on the front surface. The connecting terminal 10a is provided with a concavity 10f which is a portion recessed by about 1 to 2 mm toward inside with longitudinal length X=35 mm and lateral length Y=10 mm for preventing contamination with ink, etc. and deformation, etc. of the connecting terminal load by touching with hands during handling. Behind the cartridge is provided a fixing hook 10g (see FIG. 6A) for fixing the cartridge through engagement with the nail portion of the carriage 20. And as the characteristic point of this embodiment, a rib 11 as the positioning member is provided on substantially the straight line connecting the ink discharge port 10d and the connecting terminal 10b. The rib 11 performs positioning through engagement of the positioning member of the carriage 20 as described later.

Referring now to FIGS. 11A and 11B, the constitution of the carriage 20 is described. In these Figures, 20a is the connecting terminal bonded to the connecting terminal 10a on the carriage side of the cartridge 10, 20b the fitting portion fitted to the guide pin 10b of the cartridge 10, 20c the connecting terminal 10a, 20a the elastic member for giving an adequate pressure contact force (20 to 50 g per one terminal) during bonding or connecting of the terminal 10a, for which chloroprene rubber, urethane rubber, molprene rubber, etc. may be used as preferable material for having optimum modulus of elasticity. Numeral 21 is a positioning member formed at the concavity for effecting positioning through engagement with the positioning rib 11 of the cartridge 10. The positioning member on the inserted side is tapered as shown in FIG. 11B, 22 is a plate spring provided to take balance with the pressure forces of connecting terminals 10a, 20a, and has the hop-up function during dismantling of the cartridge as described below. Nail 23 is to be engaged with the fixing hook 10g of the cartridge 10 to fix and hold the cartridge 10 and 50 is a flexible cable for transmitting electrical signals from the recording control section not shown to the connecting terminal 20a of the carriage.

The mounting method of the cartridge in the constitution as described above is described in detail by referring to FIGS. 12A, 12B, 12C and 12D.

FIG. 12A shows the state of mounting initiation state, FIG. 12B the first state in the course of mounting, FIG. 12C the second state in the course of mounting and the FIG. 12D the state at completion of mounting.

First, as shown in FIG. 12A, when the cartridge 10 is placed on the carriage 20, the guide pin 10b of the cartridge and the surface at the bottom of the cartridge are guided by the guide surface 20h and the tip end 20t of the lock lever

20i, and moves readily in the direction A in the Figure by the weight of the cartridge 1. Next, as shown in FIG. 12B, when the guide pin **10b** is fitted into the fitting portion **20b**, the rear end portion of the recording head **10** comes off from the lock lever **20i**, to rotate the guide pin **10b** in the direction C with the guide pin **10b** as the center, whereby the fixing hook **10g** comes against the lock lever as shown in FIG. 12C. At this time, for positioning of the cartridge **10**, the side face **11a** of the rib **11** (FIG. 10B) begins to be fitted into the inside face **21a** (FIG. 11B) of the positioning member **21** of the carriage **20** to effect positioning in the direction x in FIG. 11B.

Next, when the rear end of the cartridge **10** is compulsorily pushed down in the direction D in FIG. 12C, the discharge port surface from the state as shown in FIG. 12C retracts little by little from its upper portion the elastic portion of the cap **31**. Then, the connecting terminals contact successively from the discharge port side, then the pads of connecting terminals **10a**, **20a** successively from the discharge port side, until finally the fixing hook **10g** is hooked by the nail portion **23** of the lock lever **20i** to become the state held by fixing as shown in FIG. 12D, whereby the connecting terminals **10a** and **20a** are correctly connected electrically and mechanically. At this time, the discharge port is also surely capped. At this time, the front surface **11b** of the positioning rib **11** of the recording head **10** and the inner rear surface **21b** of the positioning member **21** of the carriage **20** come against each other, whereby the positioning in the direction y in FIG. 11B is effected (see FIG. 10B, 11B).

In the constitution capable of performing the actuation as described above, since the guide pin **10b**, namely the rotation center of the cartridge **10**, is provided within the range PC in FIG. 12D upwardly of the position corresponding to the cap and in front of the position PT of the connecting terminal, the front surface (namely discharge port) and the cap **31** of the recording head element **10c**, and the connecting terminals **10a** and **20a** are adequately contacted or connected with each other without interference with other portions.

Further, by slight rubbing mutually between the connecting terminals during mounting of the recording head **10**, foreign matters existing on the terminal surface can be also shaven off or scraped off to give the action of effecting sure electrical connection.

This manner is described in more detail by referring to FIGS. 13A to 13E, 14A and 14B. FIG. 13A through 13E show the manner in which the connecting terminals are bonded to each other. FIGS. 14A and 14B are schematic illustrations partially enlarged of one of a plurality of electrode pads as unit elements of connecting terminal, showing the states at the beginning of contact and on completion of connection.

The plural number of electrode pads **13** of the connecting terminal **10a** of the cartridge **10** of this embodiment are made of lead frame of metal, etc., with the contact points being made flat. The plural number of electrode pads **24** of the connecting terminal **20a** of the carriage **20** are worked into semispherical projected shapes by application of plating to the terminal on the flexible cable **50**. Corresponding to the mounting actuation of the cartridge, first the electrode pads from the discharge port side will contact from the state in FIG. 13A as shown in FIG. 13B, and successively as shown in FIG. 13C. In transferring from FIGS. 13B to 13E, the pads are rubbed mutually one to one to maintain good electrical contact.

The pressure contact force at the contact point of the pad is controlled through deformation of the elastic member **20c**,

whereby superfluous contact force can be absorbed to give adequate pressure contact force. When mounting of the cartridge is completed, as shown in FIG. 13E, the position of the connecting terminal **20a** of the carriage is positioned lower than the position in FIG. 13A, whereby the pressure contact force is applied upwardly with the elastic member **20c**. Such pressure contact force is balanced with the forces of the nail **23** and the fitting portion **20b** of the carriage. Further, connection of the terminal is described in detail by referring to FIGS. 14A and 14B. In FIGS. 14A and 14B, I shows the contact position of the electrode pad **12** at the beginning of contact, and J the contact position of the electrode pads **13**, **24** under the final state. Through the slippage **k** between the contact points, even when foreign matters may be adhered on the contact point terminal surface, they can be scraped off to effect sure electrical connection. For connection as described above ($k>0$) to be effected, the constitution is required to be made such that the rotation center as the standard for rotation should be positioned with a predetermined distance in the direction of the normal line **13-2** of the contact portion of the electrode pad **13** of the cartridge from the tangential line **13-1** of the contact portion, and also the electrical pad **24** of the carriage **20** should be dislocated ($m>0$) when the cartridge **10** is mounted.

Next, the method for dismantling the cartridge **10** is to be described.

First, when the lock lever **20i** is moved by pressing in the direction EJ in FIG. 12D, the fixing hook **10g** is disengaged from the nail **23** to release fixing of the cartridge **10**. Then, by the plate spring **22** provided for taking balance with the connecting terminals **10a**, **20a**, the rear portion of the cartridge is hopped up through elastic force, and can be readily taken out.

Further, in the above-described embodiment of the present invention, if the ink discharge port **10d**, the positioning rib **11**, and the electrical connecting terminal **10f** are all provided so as to be overlapped with at least a part of the respective elements on substantially one straight line in the recording head element **10c**, the positional relationships of the three elements can be held with high precision. Further, in the present embodiment, the above three elements are provided on one end side where the cartridge is located, and further the cap is located on the above straight line in the home position. According to this constitution, the positioning member for carriage and electrical connecting terminals can be arranged on one side of the cartridge and the carriage, whereby an extremely advantageous constitution in aspect of practical armoring such as withdrawing of flexible cable, etc. is given, and also unsure capping due to positional slippage can be prevented to make the probability of breaking of the cartridge and the cap accompanied with mounting actuation of the cartridge much lower.

As described above, according to the mounting method of the first embodiment of the present invention, there is no breaking by way of rubbing of connecting terminals than is necessary and the cartridge will receive no bad influence from outside, and the cartridge can be positioned to the correct position of the carriage.

Further, the ink discharge port of the cartridge, the positioning member and the electrical connecting member can be arranged in this order on a substantially straight line, whereby attachment and detachment of the cartridge can be done simply and surely, while positioning the ink discharge port and the electrical connecting terminal relative to the carriage with high precision.

Thus, by one actuation of mounting of the cartridge, at least the three operations of positioning of cartridge, electrical connection, and capping can be completed.

Also, in the above second embodiment, the cap, the positioning rib and the connecting terminal are on a substantially straight line. That is, they are not completely coincident on one straight line, but a part of the respective elements are deviated from the straight line, but of course they can be made coincident with each other.

THIRD EMBODIMENT

In the first and the second embodiments as described above in detail, description has been made about the mounting actuation accompanying the rotational actuation from the upper direction to the lower direction as the direction (yz) crossing the moving direction of the carriage.

In this third embodiment, in addition to the rotational actuation in the direction (yz) as mentioned above, rotational actuation within the plane (xy) in parallel to the moving direction of the carriage. And, as the joining actuation of the connecting terminal, as different from the above first and second embodiments, rotation within a plane in parallel to the moving direction of the carriage is utilized.

Such actuations would be readily understood by addition of geometrical considerations.

Thus, still more protection of the connecting terminal can be effected, and also protection of the positioning member can be strengthened.

Also, in this third embodiment, as different from the first and the second embodiments, since two rotational actuations are accompanied, no rotation center as shown in the first and the second embodiments is provided. However, it is a constitution for accomplishing the object of the present invention, and can invariably exhibit the effect for that purpose and is of course included within the category of the present invention.

In the following embodiments, the first constitution of the present invention is that, in an ink tank integrated type, cartridge detachable relative to an ink jet recording device, the cartridge has a recording portion for ink discharging protruded forwardly from the ink tank and a positioning portion of the recording portion relative to the recording device, with the positioning portion being positioned inside of the boundary of the space formed by the boundary comprising connection mutually between the ends on the side where the recording portion is positioned and the outer surface of the recording head.

Alternatively, it is made such that in an ink tank integrated type cartridge detachable relative to the ink jet recording device, the cartridge has an ink tank, a recording portion mounted onto the ink tank, the recording portion having a base plate adhered to the ink tank and a plurality of regions for positioning of the element recording portion provided on the base plate itself, with the positioning regions being made the positioning portions of the ink tank integrated type to the main body of the recording device.

Further, it is made such that in an ink tank integrated type cartridge detachable to the carriage of the ink jet recording device, the cartridge has an electrode portion which receives driving signals from the main body of the device by electrically connecting to the power supplying portion provided on the carriage for mounting the main body, a positioning portion, which is provided around the recording portion held integrally with the cartridge, for positioning the recording portion of the cartridge into the carriage through engage-

ment with the receiving portion for positioning on the carriage, and an impeding portion for impeding electrical connection of the electrode portion with the power supplying portion and also impeding engagement of the positioning portion with the receiving portion for positioning through sliding with the carriage, the above electrical connection and the above engagement being made tolerable when the impeding portion becomes a concavo-convex engagement with the carriage.

Further, it is made such that in a carriage of an ink jet recording device for mounting a detachable ink jet cartridge, the carriage has a receiving portion for receiving the positioning on the recording portion side provided on the cartridge, a protruded portion inserted into the concavity of the cartridge and equipped with a power supplying portion to be connected electrically to the electrode portion within the concavity, a sliding portion which inhibits engagement of the positioning portion with the receiving portion for positioning and also impeding electrical connection by sliding relatively with the cartridge for mounting of the cartridge, an engaging receiving portion which affords engagement of the positioning portion with the receiving portion for positioning and electrical connection through concavo-convex engagement with the recording head, and a holding means for maintaining the mounting position of the cartridge.

Further, it is made such that in an ink jet recording device equipped with a cap for covering over the recording portion of the cartridge through adhesion to an ink jet recording head, the device has a carriage having a mounting position for mounting the ink jet cartridge at the position opposed to the above cap, a guide portion for guiding the recording head while maintaining a gap between the cap and the recording portion, so as to prevent contact of the recording portion of the cartridge with the cap, in mounting the ink jet cartridge onto the carriage in the position, a concavo-convex engaging portion to the cartridge existing on the extended line from the guide portion which affords adhesion of the recording portion to the cap substantially simultaneously with mounting of the cartridge on the cartridge positioning region of the carriage, and a cartridge holding means equipped with an elastic portion which ensures concavo-convex engagement by imparting an elastic force.

In the prior art, an exchangeable, detachable type cartridge (recording head cartridge) had a positioning portion at the position which is outer surface of the cartridge, including the end, and therefore damaging or attachment of dust, etc. sometimes occurred by falling, whereby the inherent positioning portion may come out of order.

However, according to the present invention, since the positioning portion is formed within the space where the positioning portion can be positively protected, and therefore it has become possible to effect positioning correctly even if inconveniences in operation may occur to cause falling or end contamination to occur.

Also, in integration of the ink tank and the recording head in a cartridge, the positioning of the cartridge to the main body has been effected with the ink tank as the center, and in addition, one which also effects positioning of the cartridge itself, or one having further the positioning portion of the cartridge added has been considered. However, while these proved to be poor in precision, in the present invention, since also the positioning of the cartridge of the cartridge and the recording portion of the cartridge is performed relative to the base plate of the cartridge, positioning with high precision can be accomplished.

15

Further, according to the present invention, damaging of the positioning portion, the electrode portion of the cartridge during attachment and detachment can be reduced to great extent, whereby damaging of the carriage itself relative to the cartridge can be prevented to great extent. As the result, the positioning precision can be improved to great extent. Since the electrode is located within the concavity, there is the electrode protection effect, and also lowering in positioning precision with dust, etc. attached on the electrode can be prevented.

In addition, according to the present invention, the discharge function of the head can be maintained by ensuring quickly the capped state during cartridge mounting, while preventing damaging of the cap and the head.

Those corresponding to the above expressions and the constitutions as described in the embodiment of the present inventions are included in the present invention. In the concavo-convex engagement (portion) in the above-mentioned constitutions, all embodiments are included in the present invention, provided that one is convexity, the other is concavity or a combination of both. Also, the present invention is inclusive of all combinations with any desired constitution of the above technical thoughts.

Referring now to the drawings, the present embodiment is described specifically and in detail.

FIG. 15 is a schematic perspective view of the ink jet recording device (ink jet printer) according to the embodiment of the present invention. FIG. 16A is a schematic perspective view of an ink tank integrated type recording head cartridge (recording head) to be mounted on the printer as viewed from the bottom side, FIG. 16B is a schematic perspective view of the same as viewed from the top side, FIG. 16C is a schematic bottom view of the same, and FIG. 17 is a schematic sectional view of the same. FIG. 18A is a schematic perspective view showing a constitutional example of the carriage as the mounting member for mounting the recording head, FIG. 18B and FIG. 18C are respectively a schematic top view and a schematic back view of the same.

By use of these Figures, the outline of the embodiment of the present invention is described.

First, in FIG. 15, the carriage 20 having the cartridge 10 mounted thereon is guided along the paper delivery roller 60 by the guide shaft 70, the cartridge 10 discharges ink toward the surface of the recording paper P as the recording medium, and forms an image with the attached ink droplets, thereby performing recording. Numeral 30 is the discharge restoration means located at, for example, the home position of the carriage 20. This is constituted of a cap 31 comprising an elastic material such as rubber, etc. provided for protecting the discharge port by covering over the discharge port and also preventing clogging of ink by prevention of drying of the discharge port vicinity including the discharge port, and a suction pump 33 communicated to the cap 31 through an elastic tube 32. And, by sucking ink and/or air through the discharge port by reducing the pressure internally of the cap 31 with the pump 33 to remove factors for causing defective discharge such as thickened ink, bubbles, etc., the discharging state of ink can be made good. The carriage 20 is located at the home position as the non-recording position except when the cartridge 10 performs recording, so that the discharge port may be protected there with the cap 31. And, in this embodiment, the constitution is made so that attachment and detachment of the cartridge 10 must be performed necessarily at the home position. The above constitution is substantially the same as in the first and the second embodiments as described above.

16

Next, by referring to FIGS. 16A through 16C and FIG. 17, the constitution of the cartridge is described. In this embodiment, the cartridge 10 is constituted of a recording head element 311 and an ink tank 312 which are integrated, the ink tank 312 having surfaces 312d-j, including front surfaces 312e, side surface 312j, and opposing surface 312f.

Here, the recording head element 311 is provided, as the energy generation means for generating the energy to be utilized for discharging ink, with a discharging portion 311d having an ink discharge port on the front surface (discharge port surface 311j) by use of an electrothermal transducer in the form which acts thermal energy on ink corresponding to current passage. As the energy generation means, otherwise an electromechanical transducing element, etc. can be also employed. However, the constitution is made in this embodiment by use of an electrothermal transducer, because the preparation steps are simple, the production cost is low and also high density integration of discharging ports or liquid channels communicated thereto can be effected, and a plurality of discharging ports and liquid channels communicated thereto are provided, with arrangements of electro-thermal transducers in the respective liquid channels.

Numerical 311e is a connecting terminal having the electrode portion for supplying electrical signals to the electro-thermal transducer, and in this embodiment, for example, it has dimensions of X=30 mm and Y=10 mm in FIG. 16A and arranged within the head element housing portion 310a opened on the cartridge 10 side, whereby contamination of the connecting terminal 311e with ink, etc., occurrence of damage, abrasion, deformation, dust attachment by touching with hands of the operator during handling, breaking of the electrothermal transducer by electrostatic charges are further prevented. This positional relationship is different from the embodiments in the foregoing first and second embodiments. Numeral 310b is a guide member which becomes the guide in mounting the cartridge 10 onto the carriage 20, and in this embodiment the extended] guide member (positioning portion) located on the surface 312e acting as the impeding portion which guides the recording head 10 onto the carriage 20 during mounting, and in this embodiment the extended length is made L=3 mm (see FIG. 16C) and 310c is a fixing pin (engaging section) located on the surface 312g opposed to the surface on which positioning portion 310b is found and which forms the auxiliary projection for positioning receiving the urging force for fixing the cartridge by engagement with the fixing lever 340 provided rotatably on the carriage 20 as described later by referring to FIGS. 18A to 18C. This pin may be also provided behind the base plate 313 integrally therewith, and with such constitution, further precision can be ensured.

Numerals 310d, 310e and 310f are positioning portions which form the respective standard faces in the x direction, y direction and z direction crossed perpendicularly to one another in FIGS. 16A to 16C, for fixing the cartridge 10 to a predetermined position of the carriage 20 by contacting the standard face of the carriage 20.

The respective faces 310d, 310e and 310f in these x, y and z directions are provided integrally on the base plate 313 which forms the supporting member of the discharging portion 311d of the cartridge 10, which are arranged substantially linearly to ensure readily precision in production. Also, these are provided at the position which hands, etc. of the operator can hardly touch during handling as described later, namely below the discharging portion 311d, whereby damage, deformation, and dust attachment will occur with difficulty. Further, by provision of these standard faces on the base plate (substrate) 313 nearby the discharging portion

311d, the positioning precision of the discharging portion **311d** during mounting onto the carriage **20** can be well ensured. More specifically, in this embodiment, by providing the positioning portions **310d** to **310f** inside of the boundary of the space formed by the boundary obtained by connecting mutually the ends on the side **312e** where the discharging portion **311d** is positioned (such as by connecting the leading end line **cg** and the front end line **ad** with a plane as indicated in FIG. 16B, and by connecting others of ends **a-g** and **j** as indicated in FIGS. 16A-B), it becomes possible to effect positioning accurately even if falling or contamination may occur because of inconveniences in operation. The base plate **313** can be formed of, for example, aluminum, etc. and has the function of dissipating heat as the heat dissipating plate for inhibiting temperature elevation of the cartridge **10** accompanied with driving of the electro-thermal transducer. The upper and lower portions forming the standard face **310d** (see FIG. 16B) are to regulate the slanting of the cartridge **10**, and the span (interval) should be preferably 15 mm or longer in this embodiment, and hence it was made 16 mm in this embodiment. However, this can be selected to an adequate value depending on the size of the device. Also, if regulation of the slanting poses no problem, the standard face **310d** may be also one.

Referring to FIG. 17, for introducing ink from the ink tank **312** to the recording head element **311** side, the communication pipe **311a** penetrates internally through the feeding inlet **312k** of the ink tank **312**. Also, the introducing inlet at its tip end is provided with a filter **311d**, whereby penetration of bubbles, etc. from the ink tank **3110** is impeded.

In connecting the head element **311** and the ink tank **312**, the head element **311** is urged into the ink tank **312** in the direction shown by the arrowhead A in FIG. 17. At this time, the wall portion provided with the opening **312b** of the ink tank **312** is expanded outwardly due to engagement of the projection **311b** provided on the head element **311** with the tapered surface, and simultaneously the communication pipe **311a** is penetrated into the feeding inlet **312k**.

And, when the projection **311b** and the opening **312b** reach the positions where they are completely opposed to each other, the wall portion is restored to the original position through its spring characteristic, and the projection **311b** is fitted into the opening **312b** to obtain the mounted state as shown in FIG. 17. On the other hand, the communication pipe **311a** becomes the state with the introducing inlet at its tip end pressure contacting the absorber **312a** impregnated with ink, whereby good ink communication can be obtained. In FIG. 17, **312m** is an O ring as the sealing material which ensures ink sealing at the feeding inlet **312k** portion.

According to the constitution as described above, only by pushing the head element **311** relative to the ink tank **312** in the direction shown by the arrowhead A in FIG. 17, connection of the both can be effected without requiring any step such as adhesion, etc. Also, since the communication pipe **311a** provided on the head element **311** side is permitted to penetrate into the ink tank **312** so that its tip end may pressure contact the ink absorber **312a**, ink communication can be ensured.

In the constitution as described above, the projection **311b** is provided on the head element side, and also the opening **312b** provided on the wall portion of the ink tank **312** so as to effect engagement between the projection **311b** and the opening **312b** by utilizing flexibility or elasticity of the wall portion in mounting, but the constitution at this portion can be determined as desired. For example, in place of forming

the wall portion with flexibility, even if this may be slightly rigid, the constitution may be made such that the projection **311b** is supported with a spring, etc. so as to be urged in the direction projected outwardly and fitted into the opening **312b** through the urging force of the spring when the projection **311b** is retreated inwardly accompanied with the mounting actuation as described above and opposed to the opening **312b**.

Whereas, in this embodiment, since the head element **311** is constituted to have a base plate **313** extending relatively longer integrated therewith, the mounting actuation including positioning can be made easier by utilizing this portion, and the mounted state can be made surer.

Referring again to FIG. 16C, in this embodiment, the face of the abutting member **312c** arranged on the element housing portion **310a** of the ink tank **312** against which the rear end brim **313c** of the base plate **313** is abutted is formed to a tapered surface. And, in the abutted state as shown, registration between the projection **311b** and the opening **312b** or registration between the communication pipe **311a** and the opening **312k** is effected.

Thus, in mounting the head element **311** onto the ink tank **312**, by first abutting the rear end brim **313c** of the base plate **313** against the tapered face of the abutting member **312c**, and performing the actuation as described above by referring to FIG. 17 under this state, it becomes possible to effect connection between the head element **311** and the ink tank **312**. Also, since not only joining can be effected by fitting of the projection **311b** into the opening **312b**, but also the rear end side **313c** of the base plate **313** can be pushed against the ink tank by the tapered face of the abutting member **312c**, the mounted state can be made surer.

Further, employment of such constitution of the abutting portion is advantageous with respect to working precision and with respect to difficulty of occurrence of the position disturbance with burr, as compared with the case of forming this in a right angle hook form.

Next, by referring to FIGS. 18A through 18C the constitution of the carriage **20** according to this embodiment is described.

In these Figures, **320a** is a connecting terminal which is the power supplying portion bonded to the connecting terminal **311e** of the cartridge **10**, **320b** is the guide rail which forms the sliding portion for guiding the guide member **310b** during mounting of the cartridge **10** to guide the cartridge to a predetermined position, and **320c** is an elastic member for giving an appropriate pressure contact force (e.g. 20 to 50 g per 1 pad) during bonding of the connecting terminals **311e** and **320a**, for which chloroprene rubber, urethane rubber, molprene rubber etc. may be preferably used for having appropriate modulus.

Numerical **340** is the fixed lever for performing the operation to fix the cartridge **10** to the carriage **20**, and axially supported rotatably on the carriage **20** by the shaft **341**. And, the fixing lever **340**, at the fixing position of the cartridge **10** (the position of **340(A)** shown by the solid line in FIG. 18C), pushes the fixing pin **310c** provided on the cartridge **10** in the direction C in FIG. 18C with the pressing face **340a** of the portion **3402**, and similarly in the direction D with the portion **3402**, thereby urging the cartridge **10** against the fixing position. Also, during mounting, the cartridge **10** is pressed in the direction E in FIG. 18B with the lower side brim **340c** of the fixing lever **340**. Numerical **3401** is the portion for fixing the lever **340** to the carriage during cartridge mounting.

Numerical **320d**, **320e** and **320f** are positioning receiving portions which form the respective standard faces for posi-

tioning the cartridge on a predetermined position on the carriage 20, and become the positioning standards in the x direction, y direction and z direction. That is, positioning in the x direction is effected by contacting of the x direction standard face 320d of the carriage 20 with the x direction standard face 310d provided on the base plate 313 of the recording head 10. Similarly, the positioning in the y direction is effected by contacting of the y direction standard face 320e of the carriage 20 with the y direction standard face 310e of the cartridge 10, and the positioning in the z direction by contacting of the z direction standard face 320f of the carriage 20 with the z direction standard face of the cartridge 10.

Numerical 320g is the pressing portion for pressing the cartridge 10 for contacting of the y direction standard faces 310e and 320e and 320h is the pressing portion for pressing the cartridge 10 for contacting of the z direction standard faces 310f and 320f, which forms the engagement receiving portion.

In FIG. 18A, 50 is a flexible cable to be used for transmitting driving signals from the control circuit of the device main body to the cartridge 10, etc.

Mounting actuation of the cartridge 10 onto the carriage 20 is described primarily with respect to the y direction and the z direction by use of FIG. 19 and FIG. 20.

First, the cartridge 10 is set at a predetermined position on the carriage 10 where the guide member 310b is guided by the guide rail 320b, and mounting is begun from this position (the position of 310(a) in FIG. 19).

In this embodiment, mounting actuation is done at the home position where the discharge port surface is opposed to the cap 31, but at this time, a predetermined distance Q (2 mm in this embodiment) is ensured between the discharge port surface 310i of the cartridge 10 and the cap 31 with extension L=33 of the guide member 310b (see FIG. 16C), whereby the inconvenience of contacting of the cartridge 10 with the cap 31 can be prevented.

As the cartridge 10 is slid downward under the state with the guide member 310b being guided by the guide rail 320b, the cartridge 10 is mounted to the position shown by 310(b) in FIG. 19. At this time, the rear end side of the cartridge 10 becomes the state stopped by engagement at the upper end of the pressing portion 320g, whereby further mounting is once impeded.

When the fixing lever 340 is operated from the position of 340(B) shown by the broken line in FIG. 18C to the position of 340(A), the cartridge 10 is pushed out in the E direction in FIG. 19 (y direction) with the pressing force P_3 (see FIG. 18B) given by the lower side brim 340c of the fixing lever 340, and also pushed down in the direction D in FIG. 18C with the pressing force of the pressing face 340b. By this, the rear end of the cartridge 10 comes beyond the pressing portion 320g to be set at the position shown by 310(C) in FIG. 19, thus completing the mounting actuation of the cartridge 10.

At this time, as shown in FIG. 19 and FIG. 20, on the cartridge 10 acts the force P_1 from the tapered portion of the pressing portion 320h through the guide member 310b to press the cartridge tip end portion elastically toward the carriage bottom side. Also, the force P_1' acts from the front surface toward the rear end (see FIG. 18B), and also the force P_2 acts from the pressing portion 320g through the cartridge rear end side, whereby the cartridge 10 is pressed elastically toward the cap 31 side. By this, the y direction standard face 310e of the base plate 313 of the cartridge 10 and the z direction standard face 310f, the y direction

standard face 320e of the carriage 20 and the z direction standard face 320f come into contact, respectively, whereby positioning with respect to the y direction and the z direction of the cartridge 10 is effected.

Next, the mounting actuation of the cartridge 10 onto the carriage 20 is described primarily with respect to the x direction by use of FIGS. 21A and 21B, and FIGS. 7A to 7C.

As shown in FIG. 21A, as accompanied with the operation of the fixing lever 340, its pressing face 340a is engaged with the fixing pin 310c, to act urging force in the c direction. On the other hand, on the fixing pin 310c acts the force in the D direction with the pressing face 340b (see FIG. 18C) and also the force in the E direction acts from the rear end of the cartridge 10. By the action of the force in the E direction, the cartridge 10 moves in the y direction, as shown in FIG. 21(B) whereby the portion of the base plate 313 provided with the positioning standard face 310d in the x direction comes beyond the tapered face 320d of the portion provided with the positioning standard face 320d of the carriage 20, thus effecting positioning in the x direction of the cartridge 10 through opposed contact of the both standard faces 310d, 320d on completion of mounting.

At this time, since the force acts on the cartridge 10 from the carriage 20 side through the fixing pin 310c and the x direction standard face 310d, the terminals end 311e and the 320a come into contact under pressed state.

Here, the process reaching connection between the connecting terminals 311e and 320a is described by use of FIGS. 22A to 22C. The states 22[A] to 22[C] in the Figures correspond to the respective states 310[a] to 310[c] of the cartridge 10 in FIG. 19.

First, in the process reaching from the state of 310(a) to the state of 310[b] in FIG. 19, the terminals lie, 20a are in the positional relationship shown by 310[a] in FIGS. 22A to 22C, and are not in contact with each other.

As the process from the state 310[B] to the state 310[C] in FIG. 19 proceeds, namely as the fixing lever 340 is operated, the state becomes as shown in FIG. 22B, whereby the terminals 311e, 320a begin to come into contact with each other. At the same time, the terminal 311e slides on the terminal 320a in the same direction, as accompanied with the movement of the cartridge 10 in the E direction. Therefore, in this process, even if coating or foreign matter due to ink contamination may exist or protective film may be provided, these can be scraped off to refresh the contact surface. Also, since said sliding is performed mutually one to one corresponding pads in the vicinity of their connected position, the risk of damaging terminals can be markedly reduced.

And, when mounting is completed as shown by 310[c] in FIG. 19, the terminals 311e, 320a become the state as shown in FIG. 22C, whereby a good connected state is obtained at the predetermined position.

Also, the discharging surface of the discharge portion 311d is bonded for the first time to the cap 31, whereby damaging of both during the mounting process can be prevented, and quick protection of the discharging surface after mounting can be effected.

As described above, according to this embodiment, in connecting the connecting terminals, electrical connection can be effected with the optimum force without damaging terminals, and which can refresh their surfaces, and also it becomes possible to mount the cartridge including said connection by way of simple actuation, and yet sure positioning and protection of the discharging portion can be also done on completion thereof.

We claim:

1. An ink jet cartridge for recording, said cartridge comprising:
    - a recording head having a substrate, a head portion provided with a discharge port surface on said substrate, and a discharge port provided on said discharge port surface, said substrate having a leading end line; 5
    - an ink tank having a substantially rectangular parallelopipedal shape and being capable of containing ink therein, said ink tank having a front surface, a side surface, and an opposing surface opposed to said side surface, said recording head being disposed on the side surface of the ink tank, said opposing surface having a front end line; and 10
    - a plurality of positioning portions provided on and protecting from the substrate of said head and a part of said ink tank, 15
- wherein the positioning portions project only within a space enclosed by a plane, the front surface of the ink tank, and the substrate, and the leading end line of the substrate of said recording head and the front end line of the surface opposed to the side surface or said ink tank on which said recording head is disposed lie in the plane. 20
2. An ink jet cartridge according to claim 1, wherein the positioning portions cooperatively limit the position of the cartridge upon termination of mounting the cartridge to said recording apparatus. 25
  3. An ink jet cartridge according to claim 1, said ink tank further having a surface opposed to the part and an engaging 30

section which mounts said ink tank to a carriage on said surface opposed to the part.

4. An ink jet cartridge comprising:
    - a recording head, said recording head having a substrate, a head portion having a discharge port surface on said substrate, and a discharge port provided on said discharge port surface, a part of said substrate being provided with a first positioning portion projecting from said substrate, said substrate having a leading end line; and 5
    - an ink tank, said ink tank having a substantially rectangular parallelopipedal shape and being capable of containing ink therein, said ink tank having said recording head disposed on a part thereof, a front surface parallel to the discharge port surface of said recording head, an opposing surface opposed to said part, and a second positioning portion provided on said front surface of said ink tank, said opposing surface having a front end line, 10
- wherein said first positioning portion and said second positioning portion project only within a space enclosed by a plane, said front surface of the ink tank, and said substrate, and the leading end line of the substrate of said recording head and a front end line of said opposing surface to said part on which said ink tank has said recording head lie in the plane. 15
5. An ink jet cartridge according to claim 4, said ink tank further having a surface opposed to the front surface and an engaging section which mounts said ink tank to a carriage on said surface opposed to the front surface. 20
